UNITED STATES PATENT OFFICE.

BERNARD LUTSKY AND SIMON KREISBERG, OF BROOKLYN, NEW YORK.

DESIGN FOR A PRESSURE-LIQUID VALVE.

Application filed September 1, 1925. Serial No. 14,681. Term of patent 8½ years.

To all whom it may concern:

Be it known that we, BERNARD LUTSKY and SIMON KREISBERG, both citizens of the United States, both residing in the borough of Brooklyn, county of Kings, city and State of New York, have invented a new, original, and ornamental Design for Pressure-Liquid Valve, of which the following is a specification, reference being had to the accompanying drawing, forming part thereof.

The figure is a perspective view of a pressure liquid valve, showing our new design.

We claim:

The ornamental design for a pressure liquid valve, as shown.

BERNARD LUTSKY.
SIMON KREISBERG.
